PORTABLE SCAFFOLDS AND WORK TOWERS

John M. Titzel, Fox Chapel, Pa., assignor to
Titzel Engineering Inc., Pittsburgh, Pa.

Filed Feb. 2, 1962, Ser. No. 170,747

4 Claims. (Cl. 182—128)

This invention relates to portable scaffolds and work towers and particularly to portable scaffolds adapted for use in relining hollow vessels such as the so called L-D furnace and ladles. Such furnaces and ladles pose a real problem in the handling of men and material for the relining operation, although many other furnaces and situations pose the same problems. Since the oxygen steel making furnace is typical of such problem job, I shall particularly describe the operation of this invention in the oxygen steel making furnace relining practice. It is necessary to reline the furnace after approximately 7 or 8 days of operation. By prior art practices this relining consumed approximately a week or more. This means that it has been necessary to have two furnaces available, one operating and one being relined, so that each furnace operates only 50% of its time while being relined the remaining 50%. This is a tremendous loss of time and money. The practice in the past has been to reline the furnace from the bottom as high as the workman could work satisfactorily. A wooden scaffold was then constructed stepwise in the furnace until the job was completed. Upon completion of the job the scaffolding had to be removed. The handling of material was done by the general overhead crane working in the area.

I have invented a portable scaffold structure which eliminates these problems of the prior art. My structure makes it possible to reline a furnace in less time than the time required by prior art practices. The invention eliminates entirely the need for wooden scaffolding and therefore the need for workmen to install the scaffolding. It also eliminates the continual dependence of the work upon the general overhead crane. My invention materially reduces the loss of time, labor, and materials which has characterized the prior art practices.

In a preferred form of my invention I provide an elongated tower structure adapted to pass through the opening of the object within which work is to be done. Guide means are spaced on the periphery of the tower. Leveling means are provided on the base or top portion of the tower whereby the tower may be plumbed. A carrier surrounds the tower and is slidably vertically on the guide means. Support members or arms pivoted on the carrier means are movable from a position parallel to the guide members when the structure is passed through the opening to a position transverse to the guide members whereby to form a platform. Elevator means on the tower is slidable within the tower means selectively raising and lowering the elevator and the carrier means. Preferably a removable apron is provided on the tower connecting the interior of the tower with a service floor from which work is to be done.

In the foregoing general description I have set out certain objects, advantages and purposes of my invention. Other objects, advantages and purposes will be apparent from a consideration of the following description and the accompanying drawings in which:

FIGURE 1 is a vertical section through an oxygen steel vessel showing the apparatus of this invention in use;

FIGURE 2 is a side elevation viewed from the left of FIGURE 1 of the apparatus of FIGURE 1 with the supporting members or arms folded;

FIGURE 3 is a section on the line III—III of FIGURE 1;

2

FIGURE 4 is a section on the line IV—IV of FIGURE 1; and

FIGURE 5 is a vertical section through an oxygen steel vessel showing a second embodiment of this invention.

Referring to the drawings I have illustrated a typical oxygen steel vessel 10 having an outer steel shell into which a lining of insulating brick 11, insulating cement 12 and refractory brick 13 is placed. A tower 14 with movable scaffold (more fully described later) in collapsed position according to my invention is inserted through the opening 15 of the vessel 10 by means of a conventional overhead crane or some similar means. The tower is provided at the bottom with leveling jacks 16 which rest on the bottom 17 of the furnace. The tower is plumbed by adjusting the leveling jacks. Guide members 18 are fixed at the corners of the tower and extend from the bottom of the tower to a point adjacent the opening 15 or to a height above the height of the work to be done. A carrier frame 19 is slidably mounted on the guides 18 for vertical movement thereon. Supporting members or arms 20 are pivoted on a pivot pin 21 mounted on the carrier 19 so as to be pivotable from a position in which they lie parallel to the guide members 18 (see FIGURE 2) to a position where they are normal to the guide members 18 (see FIGURE 1). The arms 20 are made in two segments 20a and 20b telescoping one within the other so as to form an extensible arm making it possible to vary the length of the arm. Brace members 22 are pinned on the arms at either anchor plate 22a or 22b depending on the position of the arms, and the carrier 19 so as to hold the arms against collapse when the arms are extended into their position normal to the guide members. Removable surface plates 23 are placed on the arms 20 to form a work surface on which the workmen may move and supplies may be stored. A hook eye (not shown) is provided on the carrier 19 which may be engaged by a latch (not shown) on elevator cage 26. When the latch is engaged in the hook eye the carrier is moved vertically with the cage to a new position. The elevator cage 26 is movable on guides 27 within the tower 14. The elevator 26 is raised and lowered through cables 28 from hoist motor 25. Access doors 29 are provided on the elevator. Hook means 29a are provided on the frame to receive removable aprons 30 which may be used as an access to the doors 29 from a service floor 31. A removable hand rail 32 is removably inserted in openings 33 in the aprons. The aprons are provided with a supporting rod 34 which engages in the hooks 29 and with a brace member 35 which engages the tower at a point spaced from the hook 29 so as to support the aprons. The elevator 26 is used to carry men and material from the working platform 23 to the service floor 31. Holes 19a are provided in the carrier frame 19 and the guides 18 to receive pins 19b which hold the carrier at any selected level.

In the embodiment of my invention illustrated in FIGURE 5, I have shown a structure basically identical with that of FIGURES 1 through 4 and carrying the identical reference numerals with the addition of the letter *a*. In the form shown in FIGURE 5, however, I have added hinge lugs 36 on the tower 14a carrying a hinge pin 37 which passes through an opening in one end of an outrigger 38 so as to permit the outrigger to pivot on the tower frame. The opposite end of the outrigger is provided with an opening 39 threadingly carrying a jack screw 40 adapted to engage the upper face 41 surrounding the opening 15a of the vessel 10a. The tower 14a is preliminarily leveled by adjusting the leveling screws 40 so as to position the tower in the furnace. The leveling jacks 16a are then positioned and adjusted to hold

the bottom of the tower frame. The outriggers may then be removed or left in place as desired. It is, of course, obvious that the leveling screws 40 might bear on a separate floor member surrounding the vessel or upon special support members above the vessel, in which case the screws 40 might be placed higher on the tower frame.

In the foregoing specification I have set out certain preferred embodiments of my invention. It will be understood however that this invention may be otherwise embodied within the scope of the following claims.

I claim:

1. A portable work tower particularly adapted for use in vessels having an opening smaller than the interior comprising an elongated tower means adapted to pass through the opening in said vessel and be normally free standing, said tower means including upper and lower portions having spaced apart vertically extending members at the corners of a quadrangle, said vertically extending members on the lower portion being provided with carrier means vertically movable thereon, base means on the lower portion adapted to engage the vessel bottom at spaced apart adjustable level points whereby the tower may be levelled and supported, a plurality of support arms spaced about said carrier means and pivoted thereon from a position parallel to the lower portion of the tower to a position transverse to the tower means to form a working platform, spaced cage guides within the upper and lower portions forming an inner cage guide extending from adjacent one end of the tower to the opposite end of said tower, cage means vertically movable on said cage guides within the upper and lower tower portions and lift means on the tower means selectively raising and lowering the cage means, said cage

5
10

means being selectively coupled with said carrier means for raising and lowering said carrier means with said cage means.

2. A portable work tower as claimed in claim 1 wherein the tower means is provided with removable outriggers extending transversely outwardly from the tower intermediate the ends thereof and terminating in free ends, jack means carried by said free ends adapted to bear on a supporting surface spaced from and surrounding the tower to provide temporary support for setting the tower.

15
15

3. A portable work tower as claimed in claim 1 wherein the carrier means is formed of generally annular members surrounding and slidably on the vertically extending members of the lower tower portion, said members being connected together to form a unitary vertically movable cage.

4. A portable work tower as claimed in claim 3 wherein the annular members of the carrier means and the vertically extending members of the lower tower portion are provided with mating openings adapted to receive locking pins to hold the carrier at a given level.
